UNITED STATES PATENT OFFICE.

JACOB BRINKERHOFF AND WARREN M. BRINKERHOFF, OF AUBURN, NEW YORK, ASSIGNORS TO THE WASHBURN & MOEN MANUFACTURING COMPANY, OF WORCESTER, MASSACHUSETTS.

METALLIC BARB-FENCING.

SPECIFICATION forming part of Letters Patent No. 241,601, dated May 17, 1881.

Application filed February 26, 1880.

To all whom it may concern:

Be it known that we, JACOB BRINKERHOFF and WARREN M. BRINKERHOFF, both of Auburn, county of Cayuga, in the State of New York, have invented certain new and useful Improvements in Metallic Barb-Fencing; and we do hereby declare that the following is a full, clear, and exact description of the same, reference being had to the accompanying drawings, forming a part of this specification, and in which—

Figure 1 represents a side view of a section of our improved metallic barb-fencing. Fig. 2 represents an opposite side view of the parts shown in Fig. 1, as will be hereinafter more fully described; and Fig. 3 represents the form of a blank barb as it appears after being cut, ready to be applied in the manufacture of our said improved metallic barb-fencing; and Fig. 20 4, a section on line A. B, Fig. 1.

To enable those skilled in the art to which our invention belongs to make and use the same, we will proceed to describe the improvement more in detail.

In the drawings, the part marked A' represents a metal strip, upon which barbs B' are secured. Barbs B' are formed from blanks B², which we prefer to cut from long strips of thin metal, since by so doing they can be cut without any loss of metal, excepting a slight shaving taken off at the point a to give that barb the desired shape; but this is not essential, and they could be made without cutting off this shaving at the point a. As indicated in Fig. 3, the pointed ends C of the barbs B' are formed by the slits or cuts b and c and the cuts a and d. After the blank barbs B' have been cut or formed, as shown in Fig. 3, they are bent or clasped about the metal strip A', so that their ends D D will nearly come together, as indicated in Figs. 1 and 4, and by which operation the pointed ends C C will be thrown out so as to project in opposite directions, as indicated in Figs. 1, 2, and 4.

Of course, if preferred, the ends C C may be made to project more or less out of line with

each other, suitable machinery being arranged for that purpose.

After the barbs B' have been applied to the metallic strip A' (and we prefer to coil up the 50 barb-strip A' upon a reel as fast as the barbs are applied thereto) it is run through a bath of molten metal—tin or zinc—and by which operation the barbs B' are secured and permanently fastened to the strip A', and the spaces 55 e between the ends D D of the barbs are filled with the zinc or tin, and also united. Consequently the barbs are strong and durable and not liable to be displaced or corroded, the tin or zinc adhering very closely and readily to the 60 newly-cut edges of the barbs.

It will be noticed that the points are formed by cutting or slitting the body of the blank from at or near its center toward each end in such manner that when the body of the barb-blank is bent or made to surround the metal strip or strand the points will project outwardly and be on that side of the strip or strand where the ends of the blanks approach or meet each other. This construction of blank avoids 70 waste of metal, and therefore is less expensive to manufacture than those barbs in which the points and confining-lips are formed by cutting the barb-blank inwardly from each end.

By cutting or slitting the blank from at or 75 near its center toward each end to form the points no specially-constructed lips or provision therefor are required, as heretofore, but that portion of the blank which is uncut, and which carries and supports the points, is brought 80 in contact with the strip or strand when bent thereon on the same side with the prongs. Therefore the barb can be secured in a fixed immovable position, avoiding all tendency to separation by twisting of the strip. The barb 85 as thus constructed can be applied without alteration in form or size to strips or strands varying in width, because the prongs are at or near the ends of the blank, and are carried by that portion of the blank which is bent around 90 the strip or strand for fastening or clinching it in position.

Having described our improvements in metallic barb-fencing, what we claim therein as new and of our invention, and desire to secure by Letters Patent, is—

5 A barb the points of which are made or formed from the body of the blank by means of slits or cuts, said points pointing toward the ends of the blank, and thrown outward by

the attaching-bends, all substantially as shown and described, and for the purpose set forth. 10

JACOB BRINKERHOFF.
WARREN M. BRINKERHOFF.
